FLOW CONTROL VALVE FOR FLUIDS

Charles F. Frye, Chicago, Ill.

Application December 10, 1957, Serial No. 48,848

Term of patent 14 years

(Cl. D91—3)

Fig. 1

Fig. 2.

Fig. 3.

Fig. 4.

Figure 1 is a perspective view of a flow control valve for fluids, showing my new design;

Figure 2 is a reduced perspective view thereof as seen from the top of Fig. 1;

Figure 3 is a plan view from above; and
Figure 4 is a plan view from below.

I claim:

The ornamental design for a flow control valve for fluids, as shown.
